UNITED STATES PATENT OFFICE

DARIUS EDGAR SHRAUGER, OF ATLANTIC, IOWA

WINDOW SCREEN

Application filed February 11, 1931. Serial No. 515,044.

The object of this invention is to provide an improved metal frame for window screens and the like.

A further object of the invention is to provide an improved window screen construction having novel means for applying screen cloth to the frame without the use of nails or screws.

More specifically, an object of the invention is to provide an improved metal window screen having means for frictionally engaging the screen cloth and holding it in stretched condition relative to the frame.

Still another object of the invention is to provide an improved construction for a metal window screen which is especially compact, light and durable, and which is adapted for readily applying or changing the screen cloth.

With these and other objects in view my invention consists in the construction, arrangement and combination of the various parts of my device, whereby the objects contemplated are attained, as hereinafter more fully set forth, pointed out in my claims, and illustrated in the accompanying drawings, in which:

Figure 1 is an elevation illustrating one face view of a window screen embodying my invention.

Figure 2 is an opposite side elevation of the same.

Figure 3 is a perspective view illustrating portions of the various members of the screen before assembling, and indicating the relative positions to be occupied in the assembly.

Figures 4 to 7 inclusive are enlarged cross sections on the line X—X of Figure 2, indicating various successive steps performed in the operation of applying and fastening the screen cloth to the frame.

Figure 8 is a similar view illustrating the method of detaching the screen cloth from the frame by using a tool.

In forming the screen I provide a rectangular frame designated by the character A. The frame A is formed of four angular bars arranged with their ends in overlapping relation and suitably secured as by welding.

Each bar is composed of a body portion 10

and a flange 12 projecting at right angles from the outer margin thereof.

Formed on the inner margin of the rectangular frame A and secured to the body portions 10 of the angular bars are ledges which are arranged on the same face of the body portion 10 as is the flange 12. Each ledge may be formed of two separate members, namely a base bar 14 and a top bar 16, suitably secured to form a rigid structure. The bars 10, 14 and 16 are arranged with their inner margins flush to form a smooth inner margin or rectangular opening for the screen frame. The base bar 14 of the ledge is of less width than the top bar 16, thus forming an undercut notch 18 opening toward the flange 12 of the frame.

A sheet of screen cloth or screen mesh 20 is provided and said sheet preferably is cut to conform substantially to the outline enclosed by the outstanding flanges 12 of the rectangular frame A.

A series of locking bars 22 are provided, one for each side of the rectangular frame A and extending substantially throughout the length of such side. The locking bars 22 preferably are of somewhat less thickness than the base bars 14 of the ledges, or in other words, of less thickness than the width of the notch 18. Each locking bar 22 is of a width corresponding substantially to the distance between the inner edge of the notch 18 and the adjacent face of the opposed flange 12 of the frame.

The screen frame when assembled comprises a unit composed of the angular bars 10—12 and the ledge bars 14 and 16.

When it is desired to apply a sheet of screen cloth or mesh such as 20 to the frame, the latter member is placed flat on a support with the flange 12 and the ledge uppermost, as indicated in Figure 4, and the sheet 20 is superposed thereon. Then the locking bars 22 are separately applied by placing them over the marginal portions of the sheet 20 above the space between the flange 12 and the ledge. The locking bars are first placed in inclined position as indicated in Figure 4 and are moved downwardly and inwardly toward the median line of the frame in the

direction of the arrow *a* in Figure 4. This movement is continued as indicated in Figure 5 to cause the marginal portion of the sheet 20 to be pressed down between the 5 ledge and the flange and into the undercut groove 18 in the form of a substantially S-shaped bend, the outer marginal portion of the locking bar being pushed downwardly along the inner face of the flange, as indicated by the arrow *b* in Figure 5, until the parts reach the position shown in Figure 6. When in this position the locking bar 22 is 10 arranged substantially parallel with the body portion 10 of the frame and is confined with one edge in the notch 18 in holding engagement with the marginal portion of the sheet 20.

The frictional contact of the close fitting locking bar 22 with the inner face of the 20 flange 12 and the grooved inner margin of the ledge member 14 serves to assist in holding the parts in this position. Provision also is made for a more positive means of holding the locking bars 22 in place, and for this 25 purpose the flanges 12 may be punched from the outer side, by the use of a tool or the like, to somewhat deform the metal and produce projections or teeth 24 on the inner faces thereof immediately above the outer edges 30 of the locking bar. This punching operation is indicated in Figure 7 as being the last step in the operation of assembling the screen, but it is to be understood that it may be formed either before or after the completion of the 35 assembling operation. In the event the projections 24 are formed before the parts are assembled, it is obvious that the locking bars 22 may be pushed down past these projections by the application of sufficient force 40 to cause the flanges 12 to spring outwardly somewhat until the locking bars 22 reach their ultimate positions.

The locking bars 22 are applied in the manner indicated on all four sides of the 45 frame and they thus serve to stretch the sheet 20 of screen cloth tightly over the frame and to hold it effectively in such position.

When it is desired to remove the locking bars 22 for the purpose of removing or replacing the screen wire, this operation may 50 be performed by the use of a pointed tool such as 26 inserted through openings 28 in the body portion 10 of the frame. The openings 28 are formed at suitable intervals and 55 adjacent the base of the flange 12 so that pressure applied by means of the tool 26 will cause the outer marginal portions of the locking bars 22 to be moved outwardly 60 past the projections 24 until they are free and clear of their locking engagement.

The window screen thus formed is light, 65 strong and durable and occupies little space as to overall width or thickness of the screen. Moreover, it is so constructed that the screen wire may be applied to the frame very easily

and quickly and without the use of any nails, screws, or similar securing means. It is also possible to easily and quickly remove the screen wire from the frame in the manner indicated, as the locking bars 22 may be 70 quickly snapped into or out of place by methods illustrated and described herein.

If desired, the rectangular frame A may be provided with a pair of knob handles 30 on one face for convenience in mounting or removing the screen from its location in a window frame or the like. It may also be formed at one margin with a projecting plate 32 extending beyond the flanges 12 for the purpose of forming a tight joint between the 75 frame and other members cooperating therewith for screening an enclosure.

The flanges 12 of the frame, in addition to the function of assisting in holding the locking bars 22, may also be useful in 80 cooperating with other members in the mounting of the screen relative to a window frame as will readily be understood by those skilled in the art.

I claim as my invention:—

1. A screen construction comprising a rectangular frame having at its outer edge a plane peripheral flange, a ledge on the frame parallel with and spaced from said flange, said ledge being formed with an undercut groove opening toward the flange, a sheet of screen cloth adapted to overlie the frame, and a series of locking bars each of which is flat and plane and adapted to fit snugly between a flange and the opposed ledge with one edge 95 engaging in said groove and holding a marginal portion of the cloth therein.

2. A screen construction comprising a rectangular frame having at its outer edge a peripheral flange, a ledge on the frame parallel with and spaced from said flange, said ledge being formed with an undercut groove opening toward the flange, a sheet of screen cloth adapted to overlie the frame, and a series of locking bars each adapted to fit snugly between a flange and the opposed ledge with one edge 100 engaging in said groove and holding a marginal portion of the cloth therein, said flanges being formed with projections on their inner faces for assisting in yieldingly holding the locking bars in place.

3. In a metal screen construction, a frame member formed with a laterally projecting flange at right angles thereto, a ledge on said frame member parallel with and spaced from said flange, said ledge being formed with a lateral groove opening toward the flange, a sheet of screen cloth arranged with one marginal portion overlapping the frame member, and a flat locking bar of a width corresponding substantially to the space between the face of said flange and the bottom of said groove, said bar adapted to be forced into said space and to carry a portion of the screen into said groove for frictionally hold- 110 115 120 125 130

ing the screen in place relative to the frame member.

4. In a metal screen construction, a frame member formed with a laterally projecting flange, a ledge on said frame member parallel with and spaced from said flange, said ledge being formed with a lateral groove opening toward the flange, a sheet of screen cloth arranged with one marginal portion overlapping the frame member, and a locking bar of a width corresponding substantially to the space between the face of said flange and the bottom of said groove, said bar adapted to be forced into said space and to carry a portion of the screen into said groove for frictionally holding the screen in place relative to the frame member, said flange being formed with projections on its face nearest to said ledge, said locking bar being capable of being snapped past said projections by application of force so that said projections serve to prevent accidental displacement of the bar.

Des Moines, Iowa, February 3, 1931.
